UNITED STATES PATENT OFFICE.

LOUIS JENSEN AND CHARLES WINTER, OF CHICAGO, ILLINOIS, ASSIGNORS TO UNITED AUTOGRAPHIC REGISTER COMPANY, OF CHICAGO, ILLINOIS, A CORPORATION OF ILLINOIS.

AUTOGRAPHIC REGISTER.

Application filed January 25, 1924. Serial No. 668,492.

To all whom it may concern:

Be it known that we, LOUIS JENSEN and CHARLES WINTER, both citizens of the United States, and residents of Chicago, in 5 the county of Cook and State of Illinois, have invented certain new and useful Improvements in an Autographic Register, of which the following is a full, clear, and exact description, such as will enable others 10 skilled in the art to make and use the same.

This invention relates to autographic registers wherein a plurality of paper strips are fed through the same across the platen and are discharged from the structure at 15 one end, and the lower strip known as the record strip is wound upon a spool or core to be stored within the casing. More particularly, the present structure relates to the mechanism for winding the record strip 20 upon the storage spool or roll and has, for its primary object, the provision of means that will automatically discontinue the winding of the record strip at a predetermined point during the delivery of each set 25 of tickets, so that a certain amount of slack is created in the record strip between the feeding mechanism and the record strip winding spool or core.

In autographic registers of the type where 30 the record strip is fed across the writing table or platen and wound upon a spool, there is a steady pull upon the strip during the winding of the spool which pull increases as the diameter of the roll on the 35 spool becomes greater. When the automatic means for stopping the delivery of the strips ceases to function at the end of each set of tickets, this pull upon the record strip frequently becomes so great as to draw this 40 strip out of alignment and often tears the same. It is to overcome this inherent objection that the present structure has been designed so as to create a slack in the record strip between the feeding mechanism and 45 the record winding spool while the ticket feeding mechanism will continue to function to the end of each set of tickets. This is done by stopping the rotation of the winding spool automatically prior to the end of 50 each set of tickets, and the structure is so made that suitable adjustment is possible for the purpose of permitting the stoppage of the record winding spool at predetermined points. This also enables the use,

within certain limits, of any length of 55 ticket in the register, and the stoppage will automatically take place at the point at which the mechanism has been adjusted.

Further advantages of the present structure reside in providing mechanism to accomplish the before-mentioned functions in 60 a novel and simple manner and with elements which may be readily assembled in registers already fabricated.

Further objects will be apparent to 65 others skilled in this art, and it is preferred to carry out the invention in substantially the manner hereinafter fully described and as more particularly pointed out in the 70 claims. Reference will now be made to the accompanying drawings that form a part 75 of this specification and which illustrate a typical or preferred embodiment of the invention.

In the drawings:—

Figure 1 is a vertical side elevation of one 75 end of an autographic register showing a portion of the driving and feeding mechanism.

Fig. 2 is a vertical end elevation, partly 80 in section, of the delivery end of the register illustrated in Figure 1 and showing the present invention incorporated therein.

Fig. 3 is a vertical section taken on line 85 3—3 of Figure 2 looking in the direction of the arrows.

Fig. 4 is a view of the structure illustrated 90 in Figure 3 showing the record strip winding mechanism in a changed position.

Fig. 5 is a horizontal section of a fragmentary portion of the structure, the view 95 being taken on line 5—5 of Figure 2.

Fig. 6 is a horizontal section taken on line 100 6—6 of Figure 1 showing in detail a portion of the strip starter mechanism.

Referring more particularly to Figures 1 and 2, it will be seen the register preferably 105 comprises a housing or casing consisting of a base 10, having vertical longitudinal side walls 11 arising from the longitudinal edges thereof and secured to the upper portions of said walls is the platen or writing bed 12, while hinged to the latter, or to the side walls, is a fenestrated cover member or plate 13 which maintains the paper strips flat 110 upon the platen. The writing is done through the window in the cover plate and the latter may be lifted on its hinges for 115

ready access to the paper strips and mani-
folding sheets for adjustment thereof. The
strips of paper are wound in the form of
rolls 14 journaled in suitable bearings 15
5 on opposite sides of the housing and the wall
at the delivery end of the register is in
the form of a gate or door 16 that is hinged
at its lower end upon a transverse, rod 17 so
that it may be dropped down for ready
10 access to the interior and said door is main-
tained in closed position by means of the
hook 18 that is engaged by a spring con-
trolled latch element 19.

Mounted within the hood 20 of the cover
15 plate and extending transversely across the
delivery end of the register is a feed roller
21, the spindle or trunnion of which at or
adjacent one end is provided with a pinion
22 that is in mesh with a pinion 23 carried
20 upon the adjacent portion of a hollow shaft
24 that is journaled in the side walls of the
register below and in vertical alinement with
feed roller 21.

Suitable friction devices in the form of
25 disks or flanged sleeves 25 and 26 are se-
cured upon the tubular shaft and are dis-
posed upon each side of the center length of
said shaft, and said disks are so located that
30 they will register with the post holes or
apertures in the paper strips as the latter
pass through the register, and when said
disks come into contact with the roller 21
through these post holes the forward feed
35 of the paper strips will be stopped. A suit-
able starter mechanism is provided to in-
itially feed the strips until such time as the
disks will again engage the strips to feed
the next set of tickets. This may be in the
40 form of a starter clutch mechanism which
will now be described. Near the center
length the tubular shaft 24 has a collar 27
secured to it, and immediately adjacent
thereto is a starter annulus or ring 28 that
is serrated upon its periphery and has a
45 conical internal bore so that in its normal
position this annulus is disengaged from the
feed roller 21 and the paper strips passing
therebetween and hangs loose or pendant
upon the tubular shaft 24, because of the
50 fact that its bore is of greater diameter than
the shaft. Mounted upon the adjacent por-
tion of the tubular shaft 24 is a cone 29,
the exterior of which corresponds in
55 angularity with the conical bore of the
annulus 28 and which is serrated as shown.
This cone is urged along the tubular shaft
toward collar 27 by means of a coiled ex-
pansion spring 30 that surrounds the shaft
60 between the base of the cone and the ad-
jacent disk 26. The cone will rotate with
the tubular shaft 24 when the latter is
actuated by the crank 31 upon its extended
end, and the cone is connected thereto by
65 means of a transverse pin 32 that passes
through a slot 33 extending longitudinally

in the tubular shaft, which pin also passes
through the adjacent portion of a solid in-
terior shaft 34 mounted within the tubular
shaft. Any suitable means are provided
70 for shifting the solid shaft within the
tubular shaft in order to engage and dis-
engage the starter clutch mechanism for
initially feeding the paper strips at the be-
ginning of each set of tickets. Mounted
75 upon the tubular shaft 24 between the side
wall and the crank 31 is a sleeve 35 having
worm threads 35^a thereon and engageable
therewith is an arm 36 having a concave re-
cess 36^a and which is rocked upon its pivot
80 62. A spring 37 pulling on a lateral finger
64 urges the arm 36 towards the worm sleeve
and shaft and maintains the same in desired
relation, and a pin 36^x passes through the
sleeve and alining slots 37^a in the tubular
85 shaft 24 in order to permit the sleeve to
rotate with but be moved longitudinally on
the shaft, due to the co-operation of arm
36 with the worm sleeve 35. This pin passes
through the adjacent end of solid shaft 34
90 and when said worm sleeve moves longi-
tudinally upon the shaft 24 it will draw
solid shaft 34 with it so as to disengage the
starter clutch elements. When the cone 29
is in engagement with the annulus 28 so
95 that it is concentric with the tubular shaft
24 worm sleeve 35 will be engaged by the
arm 36 and the annulus will be engaged
with the periphery of the feed roller 21
so that by rotating the crank the strips of
100 paper between the annulus 28 and said feed
roller will be fed forwardly so as to carry
the unperforated portions of the paper
strips over the flanged disks 25 and 26
whereupon these disks begin to feed the
105 paper. When the finger 36 disengages the
end of the worm sleeve 34, in which posi-
tion the concave portion will fall across the
end of the sleeve 34, the cone 29 will have
been entirely disengaged from annulus 28,
110 and this takes place after a few revolutions
of the crank 31, but the feeding is con-
tinued by means of the disks 25 and 26
which will revolve in contact with the feed
roller 21, and movement of the paper strips
115 will be continued until the disks register
with the next post holes.

Mounted in the side walls of the register,
120 below the shaft 24 and the feeding mech-
anism above described, is a shaft 38, the ends
of which are journaled in the register side
walls, and upon the end of said shaft nearest
the crank 31 is a pinion 39 that is secured
125 to said shaft and is operatively connected
by means of a gear train with the gear 23
heretofore mentioned. This gear train com-
prises two idle pinions 40 and 41, the former
being in mesh with gear 23 and the latter
engaging the pinion 42 upon the hub of a
large gear 43, and the latter gear is in mesh
with the pinion 39. This somewhat syn-
130

- chronizes the rotation of shaft 28 with the feeding mechanism upon shaft 24 and actuates the shaft 38 by means of the crank 31. Mounted upon shaft 38 so as to rotate therewith but capable of longitudinal movement thereon is a worm 44, the same being connected to the shaft by means of a transverse pin 45 that passes through a longitudinally elongated slot 46 in the shaft 38.
- 5 10 A coiled expansion spring 47 surrounds the shaft 38 between the gear 39 thereon and the adjacent end of the worm 44 so as to urge the latter towards the opposite end of said shaft. Mounted upon a rocker shaft 48 and
- 15 positioned below the shaft 38 is a crescent shaped arm 49 of preferably the same contour as the transverse sectional shape of the worm 44, and has, upon its adjacent face, a rib 50 that is adapted to engage the worm 20 between adjacent threads thereon. The rocker shaft is surrounded by a coiled spring 51 having one end secured thereto, and its opposite end engaging an adjacent portion of the register side wall so as to urge the 25 arm 49 toward the worm 44 and shaft 38. The normal position of this arm is shown in detail in Figure 3 of the drawings, which is at the end of the worm opposite that engaged by the spring so as to resist the urging 30 of the spring, but when the shaft 48 is rocked so as to lift the arm to the position shown in dotted lines in Figure 4 the worm will be released and the spring will push the same toward the end of the shaft. Upon 35 the arm 49 being released, it will cause the rib 50 to engage the threads of the worm, and the rotation of the worm shaft will gradually move the worm back to its normal position and permit the arm to drop again upon shaft 48 after leaving the end of the worm 40 to maintain the same in its first position with the spring contracted. The arm 49 is adjustably secured upon the shaft 48 by means of the screw 52 so that the same may 45 be set for any length of movement with the arm in engagement with the worm which will cause a predetermined length of the record strip being wound upon the spool or core prior to the creation of the slack.
- 50 55 A link 53 is connected at its lower end to the bifurcated portion of a short arm 54 projecting laterally or radially from shaft 48, and its upper end said link 53 is pivotally connected to a lateral projection 55 upon an L-shaped bell-crank. The bell-crank has its lateral arm 56 pivotally mounted upon a pin or screw 57 secured to the adjacent side wall of the register and at the end farthest from the pivot said arm 56 is provided with an extension 58 that is provided with a transverse guide pin 59 that projects through a segmental slot 60 in the side wall of the register. The arm 61 which is a part of the finger 36 is mounted upon 60 a lateral stud 62 and a depressible lever 63
- extends radially therefrom in an upwardly inclined direction. A finger 64 extends downwardly from the guide pin 59 so that when the lever 63 is depressed to raise the finger 36 from the worm sleeve, the finger 64 will move the pin 59 towards the opposite end of the segmental slot 60 which will oscillate the bell-crank upon the pivot 57 and thereby move the link 53 longitudinally and rock the shaft 48. This latter movement will 70 cause the arm 49 to move laterally away from the worm 44. The longer member 65 of the bell-crank extends at substantially right angles to the arm 56 and has upon its outer end a plurality of serrations or teeth 80 66, the purpose of which will hereinafter more fully appear.
- 85 The record strip is the lower one of the strips that are superposed upon and move across the platen, and in the present structure this record strip is designated by character R. The record strip after passing the feed roller extends downwardly to a winding spool or core 67 upon which the record strip is wound, and said core is provided 90 with a central bushing 68 of rectangular cross section. A shaft, 69, also of rectangular cross section enters this bushing and has one end extended beyond the adjacent side wall of the register, as seen in detail in 95 Figure 5 so that the same may be withdrawn to remove the spool or core to take out the record roll. Between the adjacent end of the core 67 and the side wall of the register is a disk 70 having serrations 71 100 upon its periphery, and interposed between it and the core is a circular guard plate 72. The disk 70 is provided with a centrally disposed squared opening, and surrounding said opening and extending from the 105 disk is a cylindrical sleeve 73 that passes through the side wall of the register in which it is journaled and has a gear 74 mounted upon it outside said wall. This permits the record strip core to be rotated 110 by means of the crank 31 when the register is in operation. Shaft 38 which carries the worm hereinbefore mentioned, extends outside the wall of the register and has a pinion 75 secured to it that is in mesh with a gear 76 loosely mounted upon the stub shaft 77. Between this gear 76 and the side wall of the register is another gear 78 of substantially the same dimensions as gear 76, and interposed between these gears 115 are friction elements in the form of fibre disks 79 or the like. The stub shaft 77 upon which the gears 76 and 78 are mounted is provided with a slotted head 80, and its inner end is provided with threads 81 so 120 that the same may be screwed back and forth in a threaded opening in the side wall of the register, while interposed between the head 80 of the stub shaft and the outer gear 76 is an X-shaped bowed spring 125 130

82, the tension of which may be increased or diminished by tightening or loosening the stub-shaft 77 with its head 80 against the spring. This causes the close contact between the friction disks 79, and, under ordinary operating conditions, this friction is sufficient to cause the two gears 76 and 78 to revolve together. Gear 78 is in mesh with the pinion 74 which is connected indirectly to the spool or core 67 of the record strip, and when said gear 78 is rotated the core 67 will be correspondingly moved to wind up the record strip. The teeth 66 upon the end of the bell-crank member 65 are positioned adjacent the teeth 71 on disk 70 of the record strip core, and when the arm 49 has caused the worm to move to the end of its movement, said arm will have dropped into position upon the shaft 38 upon which the worm is mounted. Likewise, the link 53 will be moved longitudinally downwardly, which will rock the bell-crank so that the serrations 66 on the end of the arm 65 thereof will engage the teeth 71 on the disk and stop the further rotation of the record strip core. This will also stop the further rotation of the gear 78, but gear 76 will continue to revolve because the frictional contact between these two gears is overcome by the stoppage of the record strip core. This stoppage may take place at any predetermined point depending upon the location of the arm 49 upon the shaft 48 and should be prior to the termination of the feeding movement of a set of tickets so that after said record strip core has been stopped the record strip will continue to be moved from the feeding mechanism and will accumulate a small amount of slack between said feed mechanism and the spool or core. Each time the lever 63 is depressed to start the discharge or feeding of a new set of tickets, the bell-crank is lifted to disengage the serrations 66 from the teeth 71 on the disk and also lifts the arm 49 from the worm to the position shown in dotted lines in Figure 4, which allows the spring 47 to move the worm to the position shown in Figure 2, after which the arm 49 will assume the position shown in full lines in Figure 4 which is in engagement with the worm. The operation is then repeated as often as a new set of tickets is fed and discharged from the register, and each time the feeding mechanism is operated a small amount of slack may be created between said feeding mechanism and the core of the record strip roll so that a binding or undue pulling of the strip is avoided.

What is claimed as new is:—

1. In an autographic register, feeding means for moving paper strips therethrough, means for winding the record strip, a worm driven by said feeding means,

an arm coacting with said worm, and means operatively connected with said arm for stopping the operation of said winding means prior to the stoppage of the feeding means said stopping means including friction devices whereby slack is created in the record strip. 70

2. In an autographic register, feeding means for moving paper strips therethrough, 75 means for winding the record strip, a worm driven by said feeding means, an arm coacting with said worm, and adjustable means operatively connected with said arm for stopping the operation of said winding means at a predetermined point prior to 80 the stoppage of the feeding means said stopping means including friction devices whereby slack is created in the record strip.

3. In an autographic register, feeding means for moving paper strips therethrough, 85 an element upon which the record strip is wound, mechanism operatively connecting said element to said feeding means, a worm driven by said feeding means, an arm coacting with said worm, and means operatively 90 connected with said arm for stopping said devices prior to the stoppage of the feeding means said stopping means including friction devices whereby slack is created in the record strip. 95

4. In an autographic register, feeding means for moving paper strips therethrough an element upon which the record strip is wound, mechanism operatively connecting 100 said element to said feeding means, frictional devices connecting portions of said mechanism, a worm driven by said feeding means, an arm coacting with said worm, and means operatively connected with said arm for stopping said winding element prior to 105 the stoppage of said feeding means whereby the friction of said devices is overcome and slack is created in the record strip.

5. In an autographic register, feeding means for moving paper strips therethrough, 110 an element upon which the record strip is wound, mechanism operatively connecting said element to said feeding means, friction devices connecting portions of said mechanism, a worm driven by said feeding means, 115 an arm coacting with said worm, and adjustable means operatively connected with said arm for stopping said winding element at a predetermined point prior to the stoppage of said feeding means whereby the friction of said devices is overcome and slack is created in the record strip. 120

6. In an autographic register, feeding means for moving paper strips therethrough, 125 a rotatable element upon which the record strip is wound, pawl and ratchet devices co-acting with said element, mechanism operatively connecting said winding element to said feeding means and including friction elements, a worm driven by said 130

- feeding means, an arm coacting with said worm, and adjustable means operatively connected with said arm for moving said pawl to cause the same to engage said ratchet at predetermined points whereby said winding element is stopped prior to the feeding means to create slack in the record strip.
7. In an autographic register, means for feeding paper strips therethrough, means for winding the record strip having frictional connection with said first means, pawl and ratchet devices co-acting with said record winding means, a longitudinally movable worm rotated by one of said means, a pivoted arm engageable with said worm and adapted to move on its pivot when disengaged from the worm at the end thereof, and means operatively connecting said arm to said pawl whereby the pivotal movement of said arm causes said pawl to engage said ratchet and thereby stop the operation of the record winding means to create slack in the record strip.
- 25 8. In an autographic register, feeding means for moving paper strips therethrough, means for winding a record strip having frictional connection with said first means, a ratchet wheel mounted upon an element of said second means, a pawl adapted to be moved to and from said wheel, a shaft rotated by one of said means having a threaded portion that rotates therewith and moves longitudinally thereon, a pivoted member movable into and out of engagement with the threaded portion of said shaft and operatively connected with said pawl and maintaining the threaded portion of said shaft normally at one of the limits of its movement, and means for temporarily disengaging said member from said shaft, whereby during the rotation of said shaft with said member in engagement with the threaded portion thereof the latter is moved to the full limit of its movement and permits said pivoted member to move off the end of the threaded portion of said shaft and thereby causes the pawl to engage the ratchet wheel and stop the winding of the record spool.
9. In an autographic register, means for moving paper strips therethrough, an element upon which the record strip is wound, a gear train operatively connecting said element to said feeding means, two of the gears of said train disposed side by side in frictional engagement with each other, a worm driven by said feeding means, an arm coacting with said worm, and means operatively connected with said arm for stopping said gear train between said side by side gears and said element whereby said feeding means continues to operate, and slack is created in the record strip.
- 65 10. In an autographic register, feeding means for moving paper strips therethrough, an element upon which the record strip is wound, gearing operatively connecting said element to said feeding means, two of the gears thereof arranged side by side, friction devices disposed between said side by side gears, a worm driven by said feeding means, an arm coacting with said worm, and means operatively connected with said arm for stopping winding element prior to the stoppage of the feeding means whereby the gears between said feeding means and said friction devices continue to operate and slack is thereby created in the record strip.
11. In an autographic register, feeding means for moving paper strips therethrough, means for winding the record strip having frictional connection with said first means, a ratchet wheel mounted upon an element of said second means, a pawl adapted to be moved to and from said wheel, a shaft rotated by one of said means, a worm sleeve slidable longitudinally on and rotatable with said shaft, a pivoted member movable into and out of engagement with said worm and operatively connected with said pawl for maintaining said worm normally at one of the limits of its longitudinal movement, and means for temporarily disengaging said member from said worm whereby during the rotation of said worm in engagement with said pivoted member the former is moved to the other limit of its movement and permits said member to move off the end of the worm and thereby cause the pawl to engage the ratchet wheel and stop the winding of the record strip.
12. In an autographic register, means for moving paper strips therethrough, means for winding the record strip having operative connection with said first means, a ratchet wheel mounted on said winding means, a pawl engageable with said wheel and normally disengaged therefrom, a worm having both rotatable and longitudinal movement, a spring urging said worm to one of the limits of its movement, a member pivoted to engage said worm after the same has been moved to the said limit of its movement, and a link connecting said member with said pawl, whereby the rotation of said worm moves the same longitudinally against said spring and when said pivoted member has disengaged the end of said worm said link is moved to cause the pawl to engage the ratchet and stop further rotation of the winding means.
13. In an autographic register including means for moving paper strips therethrough, a rotatable core upon which the record strip is wound and having a serrated flange at one end, a pawl coactable with the serrations on said flange, and means for moving said pawl into engagement with

said serrations prior to the stoppage of the paper strip feeding means, consisting of a rotatable and longitudinal slideable worm, a rock shaft, means connecting said rock shaft 5 and said pawl, and an arm adjustable longitudinally upon said shaft and co-acting with said worm whereby when said worm is rotated said arm causes the former to move longitudinally until said arm has disengaged therefrom whereby said shaft is rocked and said pawl is engaged with said

serrated flange to stop the further rotation of said winding core.

Signed at Chicago, county of Cook and State of Illinois, this 15th day of January, 15 1924.
